UNITED STATES PATENT OFFICE

166,285

TEXTILE FABRIC

Sol Weinberg, New York, N. Y.

Application January 15, 1952, Serial No. 18,061

Term of patent 3½ years

(Cl. D92—1)

To all whom it may concern:

Be it known that I, Sol Weinberg, a citizen of the United States of America, residing in New York city, county of New York, and State of New York, have invented a new, original, and ornamental Design for a Textile Fabric, of which the following is a specification, reference being had to the accompanying drawing, forming part thereof, wherein,

The figure on the drawing is a plan view of a piece of textile fabric showing my new design.

I claim:

The ornamental design for a textile fabric, substantially as shown.

SOL WEINBERG.
